UNITED STATES PATENT OFFICE

106,211

DESIGN FOR A CASING FOR AUTOMOBILE HEATER OR THE LIKE

John R. Morgan, Oak Park, Ill., assignor to
Sears, Roebuck and Co., Chicago, Ill., a corpora-
tion of New York

Application July 26, 1937, Serial No. 70,653

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Casing for Automobile Heater or the
like, of which the following is a specification,
reference being had to the accompanying draw-
ing, forming a part thereof.

Fig. 1 is a perspective view of a casing for

automobile heater or the like embodying my
new design.

Fig. 2 is a bottom plan view of the same.

The side not shown in the drawing is similar
to the side shown in Fig. 1.

I claim:

The ornamental design for a casing for auto-
mobile heater or the like, as shown and described.

JOHN R. MORGAN.
